AQUEOUS GERMICIDAL COMPOSITION
CONTAINING ALKYL PHENOLSReuben Schuler, Elizabeth, N. J., assignor to
Stanco IncorporatedNo Drawing. Application June 29, 1933,
Serial No. 678,191

4 Claims. (Cl. 167—31)

This invention relates to the preparation of improved antiseptic compositions and more particularly to the use of oil soluble emulsifying agents with alkyl phenols which are substantially insoluble in water for the preparation of compositions which are readily miscible with large volumes of water to form substantially clear "solutions" of marked germicidal power.

Alkyl phenols are known to be highly effective germicides; those alkylated phenols and homologs of phenols containing alkyl groups of four to ten or more carbon atoms are especially powerful, but are substantially insoluble in water. Germicidal compositions prepared heretofore with such alkyl phenols have consisted of solutions of the phenol in suitable organic solvents or in aqueous solutions containing large amounts of mutual solvents such as glycerine. It is necessary to use such solutions in concentrated form as they precipitate out the alkyl phenol on dilution with even relatively small amounts of water.

It has now been found that highly effective antiseptic compositions which retain their effectiveness on dilution with even 50 to 100 or more parts of water may be prepared with these alkyl phenols. Such compositions consist of a solution of the alkyl phenol in a solvent medium containing also in solution an effective emulsifying or dispersing agent. The essential characteristic of these new compositions appears to be their ability to permit dilution with even large amounts of water without appreciable formation of any separate phase; that is, the diluted compositions remain clear and show little or no turbidity or cloudiness, even on standing for long periods of time. Since these alkyl phenols are known to be insoluble in the concentrations present in such diluted aqueous compositions, it is believed that the latter compositions represent colloidal solutions in which the germicide is present in an extremely finely divided form.

Among the alkyl phenols suitable for this invention are included the butyl, amyl, hexyl, heptyl phenols, cresols, resorcinols, pyrogallols, and other alkylated phenols and homologs of phenols including hydroxy aromatics containing condensed nuclei such as naphthols. Normal and iso, primary, secondary and tertiary alkyl phenols are included. Secondary and tertiary alkyl phenols are those in which the carbon atom of the alkyl group connected to the aromatic nucleus is also connected to two or three other alkyl carbon atoms respectively. Poly alkyl phenols such as di-tertiary butyl resorcinol, di-isopropyl phenol, and the like are also included. Mixtures of alkyl

phenols prepared by reaction of a phenol with a petroleum fraction containing olefines of about three to ten carbon atoms, preferably in the presence of relatively large amounts of concentrated sulfuric acid, are especially effective.

The emulsifying agents suitable for this invention are those which are soluble in oil and which cause formation of oil in water emulsions on dilution of an oil solution thereof with large amounts of water.

The oil soluble sulfonates obtained in the refining of petroleum oils with strong or fuming sulfuric acid are an example of such emulsifying agents. The sulfonates should be preferably in a highly purified form substantially free from uncombined sulfuric acid, hydrocarbon oils, inorganic salts and asphaltic or tarry matter. It is recognized that oil soluble sulfonates of widely varying characteristics may be obtained from the different refining operations in use in the petroleum industry. The sulfonates preferred for this invention are those of the readily emulsifiable type; that is, those sulfonates which when dissolved in oil in concentrations of about 5% produce miscible oils which are readily dispersable in water, with simple agitation.

The mutual solvents suitable for this invention are those which dissolve substantial amounts of both the alkyl phenols and the emulsifying agents, and are also soluble in water. Such mutual solvents are the lower alcohols such as methyl, ethyl and isopropyl alcohols, the water soluble ketones, such as acetone, and other similar oxygenated organic compounds of relatively low molecular weight such as ethyl acetate.

The following examples represent highly effective germicidal compositions which may be prepared according to this invention.

Example 1

Two parts of secondary hexyl phenol and five parts of oil soluble sodium sulfonate are dissolved in ninety-three parts of 91% strength isopropyl alcohol. One part of this solution mixed with forty-nine parts of water yields a clear transparent solution which is strongly antiseptic, killing *Staphylococcus aureus* in five minutes, as tested by the Food and Drug Administration method, published in the United States Department of Agriculture Circular 198, of December 1931.

Example 2

Four parts of secondary hexyl phenol and ten parts of oil soluble sodium sulfonate are dissolved

in eighty-six parts of 91% strength isopropyl alcohol. One part of this solution mixed with up to 160 parts of water yields a clear solution which shows a very faint indication of cloudiness. This solution also kills *Staphylococcus aureus* in five minutes by the test mentioned in Example 1.

These compositions may be used for sterilization of buildings, instruments, bedding and clothing, for application to wounds generally, and as a personal antiseptic. Suitable perfumes and flavors, such as sugar, glucose, syrup, and the like may be added as desired. It is generally preferable to exclude oils, particularly hydrocarbon oils, from such compositions. The alkyl phenols appear to be preferentially soluble in such oils, and larger amounts of alkyl phenols are required to produce effective germicides if substantial amounts of oil are present.

29 The oil soluble sulfonates used in the above examples are prepared by the following method: A petroleum oil fraction suitable for the preparation of medicinal white oils is treated with an excess of fuming sulfuric acid. The resulting sludge is allowed to settle and is separated from the oil. The remaining upper layer of oil is neutralized with an alkali such as caustic soda or sodium or potassium carbonate or ammonia and is simultaneously or thereafter mixed with 30 an aqueous alcohol. The alcoholic solution is then allowed to settle and is separately drawn off. It contains oil-soluble sulfonates and also some inorganic salts and oil. The oil-soluble sulfonates may be separately recovered and purified 35 by various means.

One suitable method for obtaining the purified sulfonates from this solution will be described. The solution is made neutral to phenolphthalein with sulfuric acid or carbon dioxide in order to 40 neutralize any residual free alkali. The solution is then dehydrated by contacting with an agent at least equivalent in dehydrating power to sodium carbonate mono-hydrate, in sufficient quantity to substantially dehydrate the alcohol. This 45 usually requires from two to four pounds of the carbonate per gallon of water in the alcohol so-

lution treated. The temperature of treating is preferably above 32° C., the melting point of the polyhydrate salts formed. The mixture is agitated thoroughly and then settled, and the resulting upper alcohol layer is drawn off, filtered if necessary, and evaporated to dryness, leaving as a residue the purified oil soluble sulfonates which are now suitable for use as emulsifying agents. This process is described more fully in the co-pending application Ser. No. 626,233, filed 10 January 29, 1932, by H. E. Buc.

This invention is not to be limited to any theory regarding the state of aggregation of the germicides in the above described composition nor to any specific examples which have been presented 15 herein solely for purpose of illustration, but only by the following claims in which it is desired to claim all novelty insofar as the prior art permits.

I claim:

1. Germicidal and antiseptic composition comprising a solution in a water-soluble solvent of an alkyl phenol and an oil-soluble sulfonate derived from petroleum oils, said solution being miscible in water without appreciable formation 20 of a separate phase.

2. Germicidal and antiseptic composition miscible with large proportions of water without appreciable formation of a separate phase, comprising isopropyl alcohol containing in solution an oil soluble sulfonate derived from petroleum 25 oils and an alkyl phenol having 4 to 10 carbon atoms in alkyl groups.

3. Germicidal and antiseptic composition comprising a solution containing 1 to 10% secondary hexyl phenol and 2 to 20% oil soluble sulfonate 30 derived from petroleum oils in isopropyl alcohol, said solution being diluted with up to about fifty parts of water.

4. Germicidal and antiseptic composition comprising a substantially clear aqueous composition 40 containing a major proportion of water, an oil-soluble sulfonate derived from petroleum oils, a water-insoluble alkyl phenol in an effective amount, and a water-soluble solvent for said sulfonate and said alkyl phenol.

REUBEN SCHULER.
